UNITED STATES PATENT OFFICE

ISADORE H. DUBE, OF CINCINNATI, OHIO

MATCH BOX

Application filed April 23, 1932. Serial No. 607,196.

The invention relates to a box construction and more especially to a match box.

The primary object of the invention is the provision of a box construction, wherein in the tray or slide for the carriage of the matches is constructed in a particular manner so that its end can be opened, whereby matches contained therein can be readily and easily removed and such box may be placed upon an ash tray or the like and in this use will expose the butt of the matches for the free access and removal and when carried upon the person the slide or tray will prevent the accidental falling of the matches from the box, yet the same are readily and conveniently accessible with dispatch by a user.

Another object of the invention is the provision of a box construction of this character, wherein the tray or slide member for the carriage of the matches is of novel form so that in the application of the box to a holder, such as an ash tray or the like, a portion of the tray or slide can be removed, whereby the matches contained therein will have a portion of their extent exposed to permit convenient removal of the matches for the use thereof with dispatch, the removable portion of the slide member or tray being of a kind to assure strength thereto when it is usable as a flap for the carriage of the box upon the person and free and easy access is had to the latter when used in this fashion.

A further object of the invention is the provision of a box construction of this character, wherein the same in its make-up is serviceable in two ways, namely, for the retention of matches upon a holder or ash tray or the like and for carriage upon the person, the box being readily accessible so that matches may be removed therefrom with dispatch and without the loss of unused matches remaining therein.

A still further object of the invention is the provision of a box construction of this character, which is extremely simple in construction, thoroughly reliable and efficient in its purpose, strong, durable, readily and

easily opened and closed, and inexpensive to manufacture.

With these and other objects in view, the invention consists in the features of construction, combination and arrangement of parts as will be hereinafter more fully described in detail, illustrated in the accompanying drawing, which discloses the preferred embodiment of the invention and pointed out in the claims hereunto appended.

In the accompanying drawing:—

Figure 1 is a perspective view of an ash tray showing the box constructed in accordance with the invention and applied thereto, a portion of the slide member or tray having been separated to expose the matches therein for use.

Figure 2 is a perspective view of the box showing the use thereof upon the person.

Figure 3 is a view similar to Figure 2 showing the slide member or tray closed.

Figure 4 is a perspective view of the tray or slide member removed.

Figure 5 is a plan view of the blank from which the slide member or tray is made.

Figure 6 is a perspective view of a slight modified form of box.

Figure 7 is a perspective view of the slide member or tray of this modified form removed.

Similar reference characters indicate corresponding parts throughout the several views in the drawing.

Referring to the drawing in detail, A designates generally a conventional form of match box holder or ash tray or the like, this being merely shown to illustrate the application of the box construction constituting the present invention and hereinafter fully described.

The box construction forming the subject matter of the present invention comprises essentially a slide member or tray B which for convenience of storage and transportation is usually inclosed within an outer casing or shell C proportioned to engage upon the usual and ordinary mount D upon the holder or ash tray A as is clearly shown in Figure 1 of the drawing.

The slide member or tray B comprises a body made from a single blank of sheet material cut to provide a main section 10, side sections 11, end portion 12, flaps 13 and a bridging strap 14 respectively, the portions 11 being folded on crease lines 15 and likewise the end portion 12 is folded on a crease line 16, while the flaps 13 are foldable on a crease line 17 to shape the slide member or tray in the fashion shown in Figures 2, 3 and 4 of the drawing. The tongue 14 is separable from one side 11 through the medium of a weakened line 18 and this tongue is bendable at 19 and 20 respectively so as 10 to bridge a group of matches 21 as held within the slide member or tray B and illustrated in Figures 1 and 2 of the drawing.

The tongue 15 at the tip flap 22 and the area 23 respectively thereof is formed with 20 reinforcing overlapping its extensions 24, these being provided with thumb tabs 25 intermediate of the area 23 and such extensions function to reinforce the tongue 14 at the tip flap 22 and area 23 as should be 25 clearly obvious.

In the use of the match box the shell or casing C is telescoped over the mount D on the tray A and this forces the slide member or tray B of the box outwardly through 30 one end so that the tongue 14 will open to the position shown in Figure 2 of the drawing, whereupon such tongue 14 is severed at the weakened line 18 and separated from the slide member or tray B as shown in Figure 1 of the drawing, thus the butt ends of 35 the group of matches 21 held within the slide member or tray B will be exposed for access and use, the head ends of the matches being inwardly of the box.

Now if this box in the construction as heretofore described is desirable for use upon the person the tongue 14 will function to 40 permit access to the matches 21 contained in the box, it being understood of course that the said tongue 14 is not severed or removed on the weakened line 18 from the slide member or tray B and the tongue when 45 in closing position will retain the matches within the box without possibility of accidental dropping thereof from the same. The extensions 24 and the tabs 25 enable 50 the placement of the tongue into bridging relation to the group of matches 21 and also materially strengthen such tongue for continued use of the box.

In Figures 6 and 7 of the drawing there is shown a modified form of box, wherein the tray or slide member includes the main section 26, sides 27, end 28, flaps 29 and 60 tongue 30, the latter separable from the main section 26 on the weakened line 31, the said tongue being foldable at 32 and 33 to provide the tip flap 34 and bridging portion 35, the latter being externally reinforced by the overlapping tab 36, these be-

ing disposed superimposed upon the portion 35 as is clearly shown in Figure 6 of the drawing.

The match box constituting the modified form is utilized in the identical manner as 70 the preferred form hereinbefore set forth.

The shell or casing for the tray or slide member has formed therein a finger recess 75 37 which permits the user of the match box to grasp the bridging portion 35 and more particularly the tip flap 34 so that this bridging portion can be pulled outwardly from the shell or casing in a convenient manner and with dispatch as should be obvious.

What is claimed is:—

1. A match box comprising a shell, a slide member fitted within the shell and having a bridging tongue for a group of matches when contained in the slide member, said tongue being provided with a weakened line 85 between it and the slide member, said tongue further having fold lines for disposing the same in bridging relation to the matches and adapted to open and close relative thereto, and extensions folded from the tongue onto the same exteriorly thereof to reinforce said tongue.

2. A match box comprising a shell, a slide member fitted within the shell and having 95 a bridging tongue for a group of matches when contained in the slide member, said tongue being provided with a weakened line between it and the slide member, said tongue further having fold lines for disposing the 100 same in bridging relation to the matches and adapted to open and close relative thereto, and extensions folded from the tongue onto the same exteriorly thereof to reinforce said tongue, said slide member including a main 105 section, sides, end, foldable flaps and the tongue.

In testimony whereof I affix my signature.
